DESIGN FOR A COMBINATION VEHICLE VENTILATOR AND SIGNAL UNIT

William Lintern, Cleveland, Ohio, assignor, by
mesne assignments, to Evans Products Com-
pany, Detroit, Mich.

Application January 29, 1936, Serial No. 60,875

Term of patent 7 years

To all whom it may concern:

Be it known that I, William Lintern, a citizen
of the United States, residing at Cleveland, in
the county of Cuyahoga and State of Ohio, have
invented a new, original, and ornamental Design
for a Combination Vehicle Ventilator and Signal
Unit, of which the following is a specification,
reference being had to the accompanying draw-
ing, forming part thereof.

Fig. 1 is a front elevation of the ventilator and
signal unit; and

Fig. 2 is an enlarged perspective view thereof.
I claim:

The ornamental design for a combination ve-
hicle ventilator and signal unit, as shown.

WILLIAM LINTERN.
